UNITED STATES PATENT OFFICE.

NELSON T. HASENPFUG, OF GENEVA, OHIO.

DESIGN FOR A TOY BANK.

53,149.

Specification for Design.

Patented Apr. 1, 1919.

Application filed May 6, 1918. Serial No. 232,949. Term of patent 7 years.

To all whom it may concern:

Be it known that I, NELSON T. HASENPFUG, a citizen of the United States, residing at Geneva, county of Ashtabula, and State of Ohio, have invented a new, original, and ornamental Design for a Toy Bank, of which the following is a specification, reference being had to the accompanying drawings, forming a part thereof.

In said drawings, Figure 1 is a side view, Fig. 2 is a top plan view, Fig. 3 is a bot-

tom view, Fig. 4 is a rear end view, and Fig. 5 is a front end view of a toy bank showing my new design.

I claim:

The ornamental design for a toy bank, substantially as shown.

NELSON T. HASENPFUG.

Witnesses:

CHAS. L. FORD,
GLENN C. WEBSTER.
